UNITED STATES PATENT OFFICE.

LEW ROGERS, OF CARSON CITY, NEVADA.

INTERNAL-COMBUSTION-ENGINE APPLIANCE.

Application filed August 17, 1925. Serial No. 50,620.

This invention related to an internal-combustion-engine appliance, and has for its object to provide a novel combined apparatus, whereby the air used in combustion in the 5 associated internal combustion engine is,

1. Pre-heated to a maximum thermal efficiency, thereby improving carburization and increasing engine efficiency;

2. Cleaned of all dirt and dust by being 10 siphoned through a cleaning fluid, as water, thus greatly lessening wear on cylinder walls, pistons, and valves, and removing the nuclei of carbon formation inside the engine;

15 3. Partly saturated with moisture, (when water is the cleaning fluid used), whereby greater explosive energy is secured from the gaseous mixture, and carbon formation is also greatly lessened; and whereby, 20 through a more nearly perfect combustion of the gaseous mixture, dilution of the lubricating oil is lessened.

A further object of the invention is the provision of means adjustable at the will of 25 the operator to be ineffective to perform the aforesaid functions of heating, cleaning and mixing the air that is supplied to the associated internal combustion engine or to perform the aforesaid functions of heating, 30 cleaning and mixing the air either to the full capacity of the device or in any one of a plurality of proportions or degrees.

It is also an object of my invention to provide a combination device of the character 35 mentioned, with a view to compactness and cheapness of manufacture, and readiness of attachment to any stationary or automotive engine now in common use, with little or no alteration of any of the parts thereof, 40 and without interfering with the proper functioning of the engine so provided, or with any of its other attachments.

To secure the ends desired, my invention 45 consists of certain novel features, one form of which is illustrated in the accompanying drawings, and which may be described generally as a light metal apparatus, consisting substantially of the combination of an oven, open at one end and closed at the other, 50 surrounding part of the exhaust manifold of the engine. An opening near the closed end of the oven connected by a tube, through which the air, having been heated by contact with the hot exhaust manifold 55 is conducted to an elongated portion of

a rectangularly-shaped, upright cleaning chamber. A diaphragm in said cleaning chamber extending from the top thereof downward for only a portion of the depth of the cleaning chamber, which diaphragm 60 divides the cleaning chamber into two compartments at its upper part, and which diaphragm also forms, with the sides of the chamber, a continuation of the tube leading from the oven. It also makes of the chamber an inverted siphon. A cleaning fluid, such as water, is contained in said cleaning chamber to a height slightly above the lower end of the diaphragm preferably about half 65 an inch to an inch. A float chamber connected to the cleaning chamber by means of which the fluid is supplied and its proper level in the cleaning chamber maintained. A supply tank containing a supply of fluid, 70 connected to the float chamber by means of a hose, set in position slightly above the level of the fluid in the float chamber, so the fluid can flow into it by gravity. An overflow port in the float chamber above the normal level of the fluid to prevent flooding in 75 case the needle valve of the float chamber fails to function properly. A hole in the bottom of the cleaning chamber covered by a screw cap, for removing débris. A faucet 80 in the outlet pipe of the supply tank to regulate the flow therefrom. A tube leading from the top of the cleaning chamber, in the compartment other than the one above mentioned, connecting with the intake air port of the carburetor of the engine. The 85 cleaning chamber being sufficiently long, or sufficient in height to allow the collection of a reasonable amount of dirt and débris, to contain a reasonable amount of cleaning fluid, and having space enough above the 90 surface of the fluid to prevent its being drawn into the engine by suction or splashing.

In the elongated portion of the chamber, 95 there is a port opening to the atmosphere. A flap valve controls this port, which valve is hinged above the port and may be set in positions, (a) fully closed; (b) slightly open; (c) more open; (d) and entirely open. The flap valve swings into the elongated 100 portion, so that as the port is opened more and more, the elongated portion is more and more closed, thereby controlling entirely and in varying proportions, the amount of heated and unheated air admitted below the valve.

A lever is attached to one end of the valve shaft, to which is connected a rod extending through the instrument board, to which rod is attached a button, conveniently placed 5 with reference to the operator.

A similarly operated valve is placed in the upper part of the diaphragm inside the cleaning chamber and above the surface of the fluid, hinged at its lower edge, which 10 swings from a position against the diaphragm and covering a by-pass port in said diaphragm, and which valve may be set and held in several positions, as closed, slightly open, more open, and entirely open, swinging 15 into the elongated portion of the chamber; as the valve is gradually opened, it more and more directs air through the by-pass port, and less and less through the intake compartment and into the cleaning 20 fluid.

The side of the elongated portion of the chamber to which the valves are hinged is off-set or recessed so that the intake compartment offers a smooth, unbroken group 25 of surfaces to the passage of the air.

The apparatus is of size throughout sufficiently large for the unimpeded operation of the engine, for freedom from bothersome 30 frequency of attention, and is securely attached to the engine or car as close as practicable to the carburetor.

In operation, at the full capacity of the device, with both mentioned valves closing 35 their ports, the suction of the engine draws air from the atmosphere into the oven surrounding part of the exhaust manifold, where, after being heated by contact with the hot pipe or manifold, it passes from the oven into the intake tube and into the elongated portion of the cleaning chamber, and 40 down the intake compartment, into the fluid and through it, and upward through the remaining compartment of the chamber, through the second mentioned tube and into the intake air port of the carburetor and thence into the engine. In its passage 45 through the cleaning fluid, the air is washed clean of all dirt, dust and other solid particles, and is also partly saturated (if water is 50 the cleaning fluid used), with an amount of vapor, varying as the air and fluid are heated. The dirt particles settle to the bottom 55 of the cleaning chamber, whence they can be removed at intervals through the drain opening mentioned, by taking off the screw 60 cap. As the fluid is evaporated, it is replenished by the float chamber, and its level maintained at a uniform height in the chamber, as long as the supply lasts in the supply tank.

Now, in case it is not desired to heat the air to the full capacity of the apparatus, the port which opens to the atmosphere, in the elongated portion of the cleaning chamber 65 may be opened to any one of several posi-

tions, and held there, by means of which as much unheated air can be admitted, and as much heated air shut out, as may be desired.

If the temperature of the atmosphere is below the freezing point of water, any other 70 suitable cleaning fluid, as alcohol, kerosene or a mixture of water and alcohol may be used.

Also, in case it is not desired to clean and moisten the air to the full capacity of the 75 device, the port in the diaphragm, near the top of the cleaning chamber above the surface of the fluid, may be opened to any one of several positions, and held there, by means of which some, more, or all of the air 80 passes through the by-pass port into the outlet portion of the cleaning chamber, through the tube leading out of it and into the carburetor.

In case the automotive engine has an oven 85 cast integral with the exhaust manifold, (as many have), my oven can be dispensed with and the intake tube attached directly to the oven provided.

The knobs of buttons on the rods connected 90 to the levers which control the valves mentioned, fit close against the instrument board when the ports are entirely closed, and stop-nuts on the rods behind the instrument board are set at such positions as to prevent 95 the rods being pulled out too far, and injuring the valves.

The diaphragm has a horizontal lip on its lower end pointing into the main portion of the chamber and away from the intake compartment, which compels the air to pass 100 through a greater extent of fluid, insures a more nearly complete surrounding of the upward stream of air by the fluid, and allows less liability of breaking the siphon.

The valves are longer than the horizontal 105 diameter of the intake compartment, closing the intake compartment at an acute angle, to permit the incoming air to impinge upon them at an easy angle.

The rectangular form of cleaning chamber and its elongated portion is preferred to a cylindrical form with two tubes entering the chamber, as experiment shows the rectangular shape is more cheaply made and 115 is better adapted to placing the valves mentioned.

The above description is general and substantial, and I do not wish to be understood as limiting myself strictly to the precise 120 details of construction described and illustrated, as it is obvious that these details may be modified without departing from the principles of my invention. I am aware that there have been invented many forms 125 of heating, cleaning, and vapor charging, devices, but none of them, as far as I am aware, combines in one apparatus all of the functions of heating, cleaning, and moistening all of the air, or varying proportions 130

of it, or of not performing the functions of heating, cleaning and moistening, as and when desired.

In the accompanying drawings I have shown an apparatus embodying my invention in one form.

Figure 1 is a side elevation of the entire apparatus, as attached to an automobile, with the instrument board and the partition between the engine and body of the automobile shown partially in section.

Figure 2 is a detailed view in perspective of the upwardly elongated portion at the top of the cleaning chamber of the device, showing the un-heated air intake port entirely open and the heated-air tube entirely closed, and the means of hinging and operating the valve which controls the port.

Figure 3 is a side elevation of a lever, and its related parts, for operating a bypass port valve inside the cleaning chamber.

Figure 4 is a vertical section of the cleaning chamber and float chamber, in perspective.

Figure 5 is a side elevation of a second lever, and its related parts, for operating the unheated air intake valve in the elongated portion of the cleaning chamber.

Figure 6 is a vertical section of that side of the elongated portion of the cleaning chamber to which the unheated air intake valve is attached, showing how the valve is set-off into a recess in the said wall.

In Figures 3 and 5, identical numbers are used for similar parts, excepting the levers, springs and operating rods.

The same numbers refer to identical parts in the several drawings.

The exhaust manifold 9, of engine block 40 10 is partly surrounded by oven 12, which is open at the front (right-hand) end and closed at the back. Tube 11 opens out of the top of oven 12 and connects with elongated portion 15 of cleaning chamber or tank 24. Diaphragm 43 separates cleaning chamber 24 into two compartments vertically for a portion of its height, one compartment forming a continuation of the elongated portion, which, with tube 11, forms the air intake tube of the apparatus. Tube 16 connects the cleaning chamber at its top with the intake air port of mixing chamber 18, which, with fuel float chamber 17, forms the carburetor of the engine. Cleaning fluid is supplied to and maintained at a fixed height 46, above the lower end 47 of diaphragm 43 by a pipe connecting with cleaning-fluid float chamber 20. Intake pipe 21 of float chamber 20 is connected to a hose 22 which connects to an outlet pipe 25 of supply tank 28, which is supported partly by the frame of the car 27, (cut away at both ends), and securely braced to partition 8, which divides the space under the hood from the balance of

the car body, by band 29, which is bolted to said partition 8.

Cleaning chamber 24 is provided with an opening in its bottom for removal of débris, covered by screw cap 23.

Float chamber 20 has a safety over-flow pipe 48 placed above the normal level 46 of the cleaning fluid. The float chamber used is any conventional type and is not specially described. Over-flow pipe 48 is provided in case the needle valve of the float chamber 20 fails to function.

Supply tank 28 is filled through a hole in its top covered by screw cap 30.

Specially referring to Figure 2, elongated portion 15 of cleaning chamber 24 has a port open to the atmosphere in one side, indicated by reference letters, a, b, c, d. This port is controlled, (opened and closed) by a flap valve 33, hinged to shaft 32 journalled in an off-set portion 41 (Fig. 4) of elongated portion 15. Lever 14 is fastened on shaft 32, and shaft 32 is held in place by cotter pins 31. The illustration (Fig. 2) shows port a, b, c, d entirely open, and elongated portion 15 above the valve 33 entirely closed by said valve 33.

Specially referring to Figures 3 and 5, levers 14 and 25 both have notches 34 on a surface concentric to their points of support. Pawl 35 engages these notches, and is on the end of springs 13 and 19; 36 in both figures, is a pin fixed in the side of the chamber which holds the spring down in place. 37 is a cotter pin passing through a hole in support pin 38 for retaining same. 38 is a support axis for springs 13 and 19, attached to the side of the chamber. 37 is a cotter pin passing through a hole in support pin 38 for holding the springs in place. Rods 6 and 7 are bent at right angles to pass through holes in the ends of levers 14 and 25, and are held there by cotter pins 39 which pass through openings in the rods 6 and 7. Cotter pins 40 pass through openings in the shafts 32, (which similarly support valves 33 (Fig. 2) and 44 (Fig. 4)). The cotter pins 40 serve to retain the levers 14 and 25 on their respective rods 32.

Specially referring to Figure 4, 33^a shows valve 33, by dotted lines in the same position as illustrated in Fig. 2. 44 is the valve which controls the port in the diaphragm 43, and dotted lines 44^a show the valve opening the port and closing the intake compartment below the valve. 45 is the off-set portion of diaphragm 43 into which the valve 44 is placed. This valve is operated by lever 25 (Fig. 3.) and valve 33 is operated by lever 14. Both are hinged on similar shafts 32, 32.

Again specially referring to Fig. 1, 1 is a push button or knob fastened to rod 7 which passes through the instrument board 3 of the car, and also through partition 8 and connects with lever 25, which, as said above,

operates valve 44. Nut 5 on rod 7 prevents the rod being pulled out too far, and button or knob 1 comes in contact with instrument board 3 when rod 7 is pushed down to its farthest extent.

2 is a similar knob or button on the end of rod 6, which likewise passes through instrument board 3 and partition 8, and is connected to the end of lever 14, which operates valve 33. Nut 4 on rod 6 serves the same purpose as nut 5 on rod 7. Button 2 touches instrument board 3 when pushed down to its farthest extent.

47 (Fig. 4) is a horizontal lip on end of diaphragm 43 extending a short distance into outlet compartment of cleaning chamber 24 whereby the siphon is less likely to be broken by the inrush of air.

The device is supported by braces bolted to any convenient part of the engine or car.

Having thus fully described my invention, what I claim as new and wish to secure by Letters Patent is:—

1. In an attachment for internal combustion engines, an air cleaning chamber having spaced air intake and air delivery ports adjacent to its upper end and being adapted to hold a liquid below said ports, a transverse partition extending within said chamber between said ports from the top wall of the chamber below the normal level of liquid within the chamber, said partition having an air by-pass port in the portion thereof that is located above the level of liquid within the chamber, and a valve for controlling flow of air through said by-pass port, said air delivery port being adapted for connection with the air intake port of the carburetor of an associated internal combustion engine.

2. In an attachment for internal combustion engines, an air cleaning chamber having spaced air intake and air delivery ports adjacent to its upper end and being adapted to hold a liquid below said ports, a transverse partition extending within said chamber between said ports from the top wall of the chamber below the normal level of liquid within the chamber, said partition having an air by-pass port in the portion thereof that is located above the level of liquid within the chamber, a valve for controlling flow of air through said by-pass port, said air delivery port being adapted for connection with the air intake port of the carburetor of an associated internal combustion engine, and means for maintaining a constant level of liquid within said chamber.

3. In an attachment for internal combustion engines, an air cleaning chamber having spaced air intake and air delivery ports adjacent to its upper end and being adapted to hold a liquid below said ports, a transverse partition extending within said chamber between said ports from the top wall of the

chamber below the normal level of liquid within the chamber, said partition having an air by-pass port in the portion thereof that is located above the level of liquid within the chamber, a valve for controlling flow of air through said by-pass port, said air delivery port being adapted for connection with the air intake port of the carburetor of an associated internal combustion engine, the said partition having a laterally turned deflector lip at its lower end.

4. In an attachment for internal combustion engines, an air cleaning chamber having spaced air intake and air delivery ports adjacent to its upper end and being adapted to hold a liquid below said ports, a transverse partition extending within said chamber between said ports from the top wall of the chamber below the normal level of liquid within the chamber, said partition having an air by-pass port in the portion thereof that is located above the level of liquid within the chamber, a valve for controlling flow of air through said by-pass port, said air delivery port being adapted for connection with the air intake port of the carburetor of an associated internal combustion engine, said chamber having a normally closed clean-out opening in its bottom.

5. In an attachment for internal combustion engines, an air cleaning chamber having spaced air intake and air delivery ports adjacent to its upper end and being adapted to hold a liquid below said ports, a transverse partition extending within said chamber between said ports from the top wall of the chamber below the normal level of liquid within the chamber, said partition having an air by-pass port in the portion thereof that is located above the level of liquid within the chamber, a valve for controlling flow of air through said by-pass port, said air delivery port being adapted for connection with the air intake port of the carburetor of an associated internal combustion engine, an oven adapted to partially surround the exhaust manifold of the internal combustion engine, and an air conducting connection between said oven and said air intake port of the air cleaning chamber.

6. In an attachment of the character described, a tank adapted to hold a liquid in its lower part and having an air outlet port at the top of its body portion, said tank being formed to provide an air intake passage extending from above the body portion of the tank into the body portion of the tank below the level of the liquid within the body of the tank, said air intake passage being adapted at its upper end for connection with a source of heated air supply, said air intake passage also having a lateral air intake port above the top of the body of the tank and a lateral by-pass port within the body of the tank but above the level of the liquid

within the tank, said lateral air intake port being open to the atmosphere, a pivoted flap valve for closing the upper portion of said air intake passage and said lateral air intake port selectively, and a second pivoted flap valve for closing the lower portion of said air intake passage and said lateral bypass port selectively, said air outlet port being adapted for connection with the air intake port of the carburetor of an associated internal combustion engine.

7. In an attachment of the character described, a tank adapted to hold a liquid in its lower part and having an air outlet port at the top of its body portion, said tank being formed to provide an air intake passage extending from above the body portion of the tank into the body portion of the tank below the level of the liquid within the body of the tank, said air intake passage being adapted at its upper end for connection with a source of heated air supply, said air intake passage also having a lateral air intake port above the top of the body of the tank and a lateral by-pass port within the body of the tank but above the level of the liquid within the tank, said lateral air intake port being open to the atmosphere, a pivoted flap valve for closing the upper portion of said air intake passage and said lateral air intake port selectively, and a second pivoted flap valve for closing the lower portion of said air intake passage and said lateral by-pass port selectively, said air outlet port being adapted for connection with

the air intake port of the carburetor of an associated internal combustion engine, said air intake passage having laterally curved bearing portions supporting said valves.

8. In an attachment of the character described, a tank adapted to hold a liquid in its lower part and having an air outlet port at the top of its body portion, said tank being formed to provide an air intake passage extending from above the body portion of the tank into the body portion of the tank below the level of the liquid within the body of the tank, said air intake passage being adapted at its upper end for connection with a source of air supply, said air intake passage also having a lateral air intake port above the top of the body of the tank and a lateral by-pass port within the body of the tank but above the level of the liquid within the tank, said lateral air intake port being open to the atmosphere, a pivoted flap valve for closing the upper portion of said air intake passage and said lateral air intake port selectively, and a second pivoted flap valve for closing the lower portion of said air intake passage and said lateral by-pass port selectively, said air outlet port being adapted for connection with the air intake port of the carburetor of an associated internal combustion engine, and means operable at a distance from said tank for operating said valves.

In testimony whereof, I have signed my name to this specification.

LEW ROGERS.
